UNITED STATES PATENT OFFICE.

LEONARD WORK, OF WILKINSBURG, PENNSYLVANIA.

SPEED-INDICATOR.

No. 902,791.

Specification of Letters Patent.

Patented Nov. 3, 1908.

Application filed February 29, 1908. Serial No. 418,504.

To all whom it may concern:

Be it known that I, LEONARD WORK, a citizen of the United States, and a resident of Wilkinsburg, in the county of Allegheny and State of Pennsylvania, have invented a new and useful Improvement in Speed-Indicators, of which the following is a specification.

My invention relates to speed indicators, and particularly to that class of indicators in which the number of revolutions made by a shaft or other part during a predetermined period of time is registered at the expiration of that period.

15 The object of my invention is to provide a device of the character indicated that shall be very simple to operate and shall be so arranged as to eliminate the "personal equation" of the operator from the accuracy of 20 the indications.

The device is distinguished from others in that it comprises a member that is manually operable against a spring to effect operative connections between an indicator and a spindle 25 adapted to be actuated by the shaft or other part the speed of which it is desired to ascertain, and between a continuously operating clock or other suitable timing mechanism and a device for automatically determining the period of time during which the 30 said operative connections shall be maintained.

Figure 1 of the accompanying drawings is a plan view of a device that is constructed 35 in accordance with my invention, some of the parts being broken away for the sake of clearness of illustration. Fig. 2 is a view in end elevation and in section of the device. Fig. 3 is a plan view looking upwardly at 40 the top plate of the device, and Fig. 4 is an enlarged perspective view of some of the parts.

Mounted upon the upper face of a casing 1 that contains any suitable clock mechanism 2 comprising a pinion 3 is a device 4 for indicating the number of revolutions made by a spindle 5 having a sharpened outer end adapted to be inserted into the end of a shaft, or that may be provided with other 45 suitable means for obtaining rotary motion from another part. The indicating device 4 comprises a stationary dial plate 6 and an overlapping disk 7 having its edge beveled and provided with an index 8 adapted to

register with the subdivisions upon the dial plate 6. The disk 7 is mounted upon the outer end of a short shaft 9 that projects through a slot 10 in the stationary dial plate 6 and carries, near or at its middle, a gear 11 adapted to mesh with a worm gear 12 formed upon the inner end of the spindle 5. The gear ratio and the subdivisions upon the dial plate 6 are so adjusted with respect to each other that one revolution of the spindle 5 will cause the index 8 to move over one 65 division of the dial, and, by reason of the provision of the slot at 10 in the dial plate, the shaft 9 may be moved transversely of its axis sufficiently to permit of effecting engagement or disengagement between the 70 gears 11 and 12.

Movement of the gears 11 and 12 into and out of engagement is effected by means of a bifurcated arm 13 that may be moved downwardly to the position shown in full lines in 75 Fig. 3 by means of a button 14 that projects from the side of the casing at a convenient location to be pressed by the finger of the operator and is normally maintained in its uppermost position by means of a spring 80 15. Rotatably mounted at the free end of the said arm and rigidly connected together are a disk 16 having notches in its periphery and a gear 17 adapted to engage with the pinion 3 of the clock mechanism when the 85 button 14 is pressed inward; *i. e.*, when the arm 13 occupies the full line position in Fig. 3.

The gear 16 is maintained in operative engagement with the pinion 3 during the time 90 that a stop 18 bears upon the edge of the disk 17, and is permitted to become disengaged therefrom when a notch in the disk is brought opposite the stop, the spring 15 serving to cause the stop to occupy one of 95 the notches and to thereby effect such disengagement automatically. The notches in the periphery of the disk are spaced at such intervals that suitable predetermined periods of time, such, for instance, as half minutes or minutes, will elapse between the time when the stop 18 is released from one notch until it is caused to occupy the next notch. The arm 13 is also provided with a pin 19, that projects into a recess in a screw 20 that 10 is threaded in the inner end of the shaft 9, the said pin serving to move the gear 11 into and out of operative engagement with the

worm gear 12 simultaneously with the movement of the gear 16 into and out of operative engagement with the pinion 3.

In the operation of the device, the disk 7 is first moved so as to bring the index 8 thereon opposite the zero or other suitable mark or division upon the dial plate 6, which may be readily done when the button 14 is in its outermost position because there is then no connection between the said disk and the spindle. The spindle 5 is next applied to the end of the shaft, or to any other part the speed of operation of which it is desired to ascertain, and when it has been carefully centered, or when it is desired to cause the registration to begin, the button 14 is pressed, thus causing the gear 16 to mesh with the pinion 3, the gear 11 to mesh with the worm gear 12 and the stop 18 to release the notched disk 17. The motion of the spindle 5 will then be transmitted to the index disk 7, while the clock pinion 3 will effect rotation of the gear 16 and of the disk 17. When the disk 17 has been rotated slightly the notch therein that was previously occupied by the stop 18 will be moved out of alignment with the stop, and the button 14 may be released, the stop 18 then bearing upon the periphery of the disk and thereby serving to prevent interruption of the operative connections between the gears 3 and 16 and between gears 11 and 12. When another notch has been brought opposite the stop, the arm 13 will be moved automatically by the spring 15 to cause the stop to enter the notch and to cause severance of the said operative connections. The division upon the dial 6 then lying opposite the index 8 represents the number of revolutions made by the spindle 5 during the period predetermined by the distances between the notches in the disk 17. Thus it is seen that the index of the indicating device may be readily and conveniently set at the zero or other desired position, that the spindle may be carefully centered with or otherwise adjusted with respect to the rotating member without interfering with the setting of the indicating device, and that no delays in the operation occur owing to delays in the starting of the clock mechanism.

I claim as my invention:

1. The combination with a rotatable member, an indicating device, and continuously-operating clock mechanism, of a movable member, time-measuring means carried thereby, means governed by the movable member for effecting operative connections simultaneously between the clock mechanism and the time-measuring means and between the indicating device and the rotatable member,

and means coöoperating with the time-measuring means to either maintain or permit interruption of said operative connections. 65

2. The combination with a rotatable member, an indicating device, and continuously-operating clock mechanism, of a movable member, time-measuring means carried thereby, means governed by the movable member for effecting operative connections simultaneously between the clock mechanism and the time-measuring means and between the indicating device and the rotatable member, and means for effecting interruption of said 70 connections at the expiration of a period predetermined by the time-measuring means. 75

3. The combination with a rotatable member, an indicating device, and continuously-operating clock mechanism, of a movable member, a notched wheel carried thereby, means governed by the movable member for effecting operative connections simultaneously between the notched wheel and the clock-work and between the indicating device and the rotatable member, and a stationary detent adapted to engage the periphery of the wheel in order to maintain the said connections or to occupy the notches therein in order to permit interruption of 80 85 90 said connections.

4. The combination with a normally freely rotatable member, an indicating device, continuously-operating clock mechanism, and time-measuring means, of manually actuated means independent of the rotatable member for effecting operative connections simultaneously between the clock mechanism and the time-measuring means and between the indicating device and the rotatable member, and means for thereafter maintaining said operative connections during a period predetermined by the time-measuring means. 95 100

5. The combination with continuously-operating clock mechanism, time-measuring means, a rotatable member, and an indicating device comprising a member normally movable independently of other parts, of means for effecting operative connections simultaneously between the rotatable member and the indicating device and between the time-measuring means and the clock mechanism, and means for automatically interrupting the said connections at the expiration of a period predetermined by the 105 110 115 time-measuring means.

In testimony whereof, I have hereunto subscribed my name this 24th day of February, 1908.

LEONARD WORK.
